UNITED STATES PATENT OFFICE.

EDMUND C. MORGAN, OF NEW YORK, N. Y., ASSIGNOR TO AMERICAN MORGAN COMPANY, OF CHICAGO, ILLINOIS, A CORPORATION OF SOUTH DAKOTA.

MINING-MACHINE.

1,271,197.

Specification of Letters Patent.

Patented July 2, 1918.

Application filed May 28, 1904, Serial No. 210,174. Renewed November 28, 1917. Serial No. 204,452.

To all whom it may concern:

Be it known that I, EDMUND C. MORGAN, a citizen of the United States, residing at New York, in the county of Queens and 5 State of New York, have invented a new and useful Improvement in Mining-Machines, of which the following is a specification.

This invention relates to mining machines.

The object of the invention is to provide 10 a mining machine, and especially a mining machine of the type known as pick mining machines, which is simple in construction and efficient in operation.

A further object of the invention is to 15 provide an improved mining machine wherein the mining tool is, under the control of an operator advanced to its work and is operated to effect the mining operation.

A further object of the invention is to 20 provide an improved mining machine wherein the mining tool may be moved in a vertical plane and also in a horizontal plane so as to effect the mining operation throughout the entire transverse area of the wall of 25 material to be mined.

A further object of the invention is to provide improved means which are simple and efficient for removing the mined material.

30 A further object of the invention is to provide improved means which are simple and efficient, and within the control of the operator, for advancing the framework upon which the mining mechanisms are mounted 35 as the mining operation continues.

A further object of the invention is to 40 provide controllable means for anchoring the mining tool supporting frame against recoil movement due to the delivery of the blow of the mining tool.

A further object of the invention is to 45 provide an improved mining machine employing a reciprocable mining tool, with means for moving such tool in universal directions so as to enable it to command the entire transverse area of the wall of material to be mined, thereby avoiding the necessity for resorting to blasting to effect a mining of the material.

50 A further object of the invention is to provide a mining machine in which a reciprocable mining tool is mounted for universal movement to command the entire transverse area of the wall of material to be mined, wherein the mined material is auto-

matically removed, and power mechanisms for controlling the movements of the tool, and the operation of the removing mechanism is readily controllable by a single attendant on the machine.

Other objects of the invention will appear more fully hereinafter.

The invention consists substantially in the construction, combination, location and arrangement of parts, all as will be more fully 65 hereinafter set forth, as shown in the accompanying drawings, and finally pointed out in the appended claims.

Referring to the accompanying drawings, and to the various views and reference-signs 70 appearing thereon,—

Figure 1 is a view in vertical longitudinal section of a mining machine embodying the principles of my invention, the plane of section being indicated by reference line 1—1, 75 Fig. 2, looking in the direction of the arrows.

Fig. 2 is a view in rear elevation of a mining machine embodying the principles of my invention, the delivery belt for the material 80 mined being shown in vertical transverse section.

Fig. 3 is a top plan view of the same, parts broken out and parts in horizontal section.

Fig. 4 is a view in front elevation, parts 85 broken out and parts in vertical transverse section, on the line 4—4 of Fig. 1, looking in the direction of the arrows.

Fig. 5 is a horizontal section on the line 5—5, Fig. 1, looking in the direction of the 90 arrows.

Fig. 6 is a side elevation of the machine shown in Fig. 1.

Fig. 7 is an enlarged sectional view of the cylinder for advancing and retracting the 95 scoop or shovel.

The same part is designated by the same reference-sign wherever it occurs throughout the several views.

In the construction and operation of mining machines, and particularly machines of the type called pick-mining machines, where the mining tool operates percussively and is mounted upon a frame or carriage adapted to be advanced toward the end wall of a 100 room or entry to effect the mining operation, it is important and desirable to provide means whereby the mining tool is enabled to command the entire area of the end wall of the room or entry so as to effect the 105 110

mining operation throughout the entire transverse area of such wall, and to this end it is desirable to provide means for operating the mining tool and also for so shifting 5 or moving the tool that it will not only be operated, but will be moved both horizontally and vertically, and also will be advanced as the mining operation proceeds.

It is also desirable to provide means for 10 efficiently advancing the frame upon which the tool is mounted as the mining operation proceeds, and to anchor the same in advanced position and against recoil due to the delivery of the blow of the tool while effecting 15 the mining operation.

It is also desirable in machines of this class and so as to avoid interruption of the mining operation to provide means which are simple and efficient for removing the 20 mined material as the mining operation proceeds, thereby enabling the machine to be continuously operating without interruption for the purpose of removing the mined material.

25 It is also desirable that the various mechanisms for accomplishing the objects and operations above stated be efficiently controlled by the machine operator.

It is among the special purposes of my 30 present invention to provide a construction of pick or similar mining machine, wherein the desirable objects above stated are accomplished and in a most efficient manner.

In the accompanying drawings I have 35 shown a construction and arrangement of mechanism embodying the principles of my invention, and which embodies the best form in which I at present contemplate carrying the invention into practical operation, but 40 which is capable of modification and change in the various details of construction and arrangement of the parts thereof, without departure from the spirit and scope of my invention. While, therefore, I have shown 45 and will now describe the specific construction and arrangement of one embodiment of my invention, I do not desire to be limited or restricted thereto.

In the drawings, reference-sign A designates the frame-work of the machine, upon 50 which the various operating parts are mounted. Upon the side-pieces of the main frame A are mounted guides B, adapted to receive a sliding frame C. Pivotally connected to the sliding frame C is a tool frame D, the pivotal connection of the tool frame 55 to the sliding frame being in the form of a vertically arranged stud E, shown in full lines in Fig. 1, and in dotted lines in Fig. 3, 60 said stud forming a vertical axis about which the tool frame D may swing horizontally. The tool support is indicated by reference sign F, and is pivotally connected by means of a horizontally arranged stud G, 65 upon the tool frame D, whereby the tool

support may be rocked or swung in a vertical plane. The particular form of mining tool selected for the purposes of illustration is an ordinary style of pick H, and is suitably mounted in the tool support F for operation. This tool may be operated by any suitable or convenient motor. In the form shown, to which, however, my invention is not to be limited or restricted, I form the tool support into a cylinder J, in which operates a piston K, the stem of the pick or other tool being connected to the piston. L designates a supply pipe for supplying an operating medium to the machine, such, for instance, as compressed air. Communicating with supply-pipe L is a delivery pipe M, and which may be controlled in its connection with the supply pipe in any convenient manner, as, for instance, by means of a hand-valve N, (see Figs. 1 and 3.) The delivery pipe M delivers into a valve chest O, in which is arranged to operate a valve P, for controlling the supply of the operating medium to opposite ends of the cylinder J. The valve P may be operated automatically 90 in any convenient manner, as, for instance, by means of a valve rod or stem Q, having its ends projecting through the casing of the valve chamber and in the path of the ends of rocker levers R, R pivotally mounted 95 upon the casing of cylinder J, the opposite arms of said rocker levers being arranged in the path of pins S, arranged on opposite sides of and adapted to be alternately engaged by the piston K in the reciprocating 100 movements thereof, said pins operating through openings or boxes formed through the walls of cylinder J, so that when the piston K approaches one limit of its reciprocatory movement it will engage one of the pins S and project the same outwardly through the cylinder casing and against one arm of its associated rocker lever R, thereby 105 rocking said lever and causing the other arm thereof to engage valve stem Q, and project the same in the opposite direction to shift the valve into position to admit the operating fluid to the opposite side of the piston, and when the piston K approaches the opposite limit of its reciprocatory movement within cylinder J, said piston engages the other pin S, thereby projecting the same 110 through the cylinder casing and effecting a rocking movement of rocking lever R on the opposite side or end of the cylinder, 115 thereby shifting the valve P back in the opposite direction to that above described, and in each movement of the valve P, one end or the other, as the case may be, of the tool operating cylinder J is opened to exhaust. As 120 the parts are shown in Fig. 1, the right-hand end of the cylinder J is opened to receive a supply of the operating medium preparatory to projecting the tool or pick H while the opposite or left-hand end of cylinder J 125

is shown open to exhaust, the exhaust connection being indicated at T. In this manner the tool H is continuously operated, and may be arrested or started by suitable manipulation of valve N.

As above stated, I do not desire to be limited or restricted to the particular form of motor employed for actuating the pick or other tool, as it is obvious that the same may be operated by steam or hydraulically, or by any other suitable or convenient form of motor. That shown, however, I consider most practical and efficient.

I will now describe means for advancing the sliding frame C upon the main frame A.

Reference sign A' designates a cylinder, the casing of which is rigidly mounted and connected to or formed with the sliding frame C. In this cylinder is arranged a piston B', the rod or stem C' of which is rigidly bolted or connected, as, for instance, at D', to the main frame of the machine, or to a cross-bar E' thereof. By admitting an operating medium to cylinder A' on one side or the other of piston B', said piston being held stationary, the cylinder A' is caused to move longitudinally, and since said cylinder is rigidly connected to or is formed with the sliding frame C, it is obvious that said sliding frame and the parts supported thereby will partake of the longitudinal movement of cylinder A'. While I have shown a cylinder and piston motor for effecting the sliding movements of sliding frame C, I do not desire to be limited or restricted thereto, as any suitable or convenient form of motor for effecting the desired result may be employed. The form of motor shown, however, is practicable and efficient. In the particular form of motor shown any desired operating medium whether liquid or fluid may be employed. In practice, however, I prefer to employ a liquid, as, for instance, water, for reasons which will be explained hereinafter. The supply and exhaust of operating medium to and from cylinder A' may be controlled in any convenient manner, as, for instance, by means of a valve F'. Where the operating medium employed in cylinder A' is water or other fluid I provide a reservoir G', (see Fig. 1,) to receive the operating medium. From this reservoir the water or other fluid is drawn from said reservoir by means of a pump piston H', operating in a cylinder J', through suitable valve controlled openings or passages K', L', the fluid being delivered from cylinder J' into a chamber M', through valve controlled ports N', the operation being that when the pump piston H' is moved in one direction, say from the left toward the right, as seen in Fig. 1, the operating fluid is drawn from reservoir G' through port K', into cylinder J', while any operat-

ing fluid contained in cylinder J' on the opposite side of piston H' is expelled or delivered from cylinder J' through the port N' at the right-hand end of cylinder J', and into the chamber or passage M'; and 70 similarly when the piston H' is moved in the opposite direction,—that is, from the right-hand end of cylinder J', toward the left-hand end thereof,—operating fluid is drawn into the cylinder J' from reservoir 75 G', through port L', while the operating fluid previously drawn into the left-hand end of cylinder J' is expelled or delivered therefrom through the valve controlled port N', at the left-hand end of cylinder J', 80 and into the chamber or passage M'. A passage O' delivers from chamber M' to cylinder A', said passage being controlled by a valve F'. An exhaust passage P', Q', delivers from cylinder A' to reservoir G', and 85 is also controlled by valve F'. The parts are shown in Fig. 1 with the valve F' opening communication between the left-hand end of cylinder A' and chamber M' to admit the operating medium to cylinder A' at that end 90 thereof, while the right-hand end of cylinder A' is shown open to exhaust. By suitably manipulating the valve F', however, the chamber M' and passage O' may be thrown into communication with the right- 95 hand end of cylinder A', and simultaneously the left-hand end of said cylinder is opened to exhaust at reservoir G'.

The pump piston H' may be operated in any suitable or convenient manner, and automatically, or by any suitable arrangement of motor. I have shown a simple construction of motor for accomplishing this operation, and comprising a cylinder R', in which operates a piston S', an operating medium being introduced in cylinder R', and alternately on opposite sides of piston S', in any suitable manner, as, for instance, by means of a valve T', having a stem A², and operated by means of tumbler levers B², and pins C², in identically the same manner as that above described with reference to the motor for operating the pick or tool H, said valve operating to control the supply and exhaust of an operating medium to cylinder 100 R'. The particular operating medium is unimportant and may be either fluid such as air or a liquid such as water. I have shown, however, a pipe connection D², communicating with the compressed air supply pipe L, and delivering into the chamber of valve T'. This pipe D² is provided with a hand operated valve E², by which the supply of operating medium to operate the pump actuating piston S' may be turned on or off 110 115 as desired.

If desired, the fluid in chamber M', and which is admitted to cylinder A' under the control of valve F', may be maintained under any desired degree of pressure. To 120 125 130

this end I may employ any suitable or ordinary form of compressor. I have shown a simple form of compressor or accumulator, comprising a piston F^2 , operating within a cylinder G^2 , and provided with a plunger H^2 and operating in a cylindrical bore J^2 , which communicates with chamber M' . The piston H^2 forms a partition within cylinder G^2 , and a suitable compressor medium is admitted to cylinder G^2 above piston F^2 . This may be accomplished in any convenient manner, as, for instance, by means of a pipe or other connection K^2 , from main supply pipe L , and in which may be located a hand valve L^2 for controlling the supply of pressure medium from main supply pipe L through pipe K^2 into the upper end of cylinder G^2 , above piston F^2 . The lower end surface of plunger H^2 is exposed to the pressure of the operating medium in chamber M' , while the upper surface of piston F^2 is exposed to the pressure of the pressure medium admitted to the upper end of cylinder G^2 . By suitably regulating the pressure thus supplied to the upper end of cylinder G^2 , it is obvious that the medium delivered by the pump piston H^2 into chamber M' may be maintained in said chamber M' at any desired degree of pressure. As above indicated, however, the particular form or construction of compressor or accumulator is unimportant, as many specifically different forms may be employed without departure from the spirit and scope of my invention in this respect.

I have above stated that I prefer to employ water as the operating medium for cylinder A' but air may be used if desired. The reason for water as a preferable operating medium at this point is that by reason of its characteristic of non-compressibility, it may be employed by suitably manipulating valve F' as an operating medium to cause the cylinder A' to travel or move longitudinally upon its piston B' and to advance the slide frame C . When the desired extent of advancement of said frame has been effected, by simply cutting off the supply and exhaust of the water to and from cylinder A' , the body of water remaining within the cylinder A' and on opposite sides of piston B' , forms, in effect, a lock to hold the sliding frame C in the position thereof to which it has been advanced or removed.

I have above indicated that the frame D is pivotally connected to sliding frame C upon a vertical pivot-stud E , so that said frame D may be rocked or swung horizontally in the operation of the machine. I have also explained that the tool support F was pivotally connected upon a horizontal axis or pivot stud G to the tool frame D , so that the tool support carrying the tool may be rocked or swung vertically to effect the mining operation. It is important that the horizontal and vertical swinging movements of the mining tool thus permitted be effected independently of each other, so as to enable the tool to command the entire transverse face or surface of the wall to be mined, and in accordance with the principles of my invention I propose to provide power actuated means and independent of each other and under the ready control of an attendant for effecting the rocking or swinging movements referred to. In Fig. 1 I have shown in detail the power actuated mechanism for rocking or swinging the cutter support F about its horizontal pivot stud or axis G . Of course, it is obvious that any suitable or convenient form or construction of motor for accomplishing this result, and which may be arranged under the control of the machine attendant, may be employed for this purpose. While, therefore, I have shown and will now describe one form of construction for accomplishing the desired object, I do not desire to be limited or restricted to the particular construction shown.

M^2 designates a cylinder, which is mounted upon, carried by or formed with the tool frame D to rock or swing therewith. Within cylinder M^2 is a piston N^2 , the rod or stem O^2 of which is connected to a cross-head P^2 , to which is pivotally connected one end of a link Q^2 , the other end of said link being pivotally connected to a crank arm R^2 , connected to pivot stud G . From this description it will be seen that when the piston N^2 is shifted in one direction or the other pivot stud G is rotatively actuated in one direction or the other, according to the direction of movement of the piston N^2 . This pivot stud is splined in its bearing seat in the tool support F , so as to secure coincident rocking or swinging movement of the tool frame. Operating medium may be supplied to cylinder M^2 for actuating piston N^2 in any suitable or convenient manner. Although compressed air may be used if desired, in practice I prefer to employ hydraulic power in this connection, for the reason that thereby I am enabled to lock the piston N^2 in any desired position in a manner similar to that above described with reference to the locking of cylinder A' , and by locking piston N^2 in any desired position against movement it is obvious that the tool support F will be held in any desired position of vertical inclination. Where water is employed as the operating medium I provide a pipe S^2 leading from and communicating at one end with chamber M' into a casing T^2 , in which casing is arranged a passage, controlled by a valve A^3 . Pipes B^3 , C^3 , lead from the valve chamber or the passage controlled by valve A^3 into the respective ends of cylinder M^2 . An exhaust pipe D^3 also communicates with the passage which valve A^3 controls,

said exhaust pipe delivering through pipe connections E³, Q', into reservoir G'.

It should be observed that the pick machine comprising the pick and the means for operating the same percussively is mounted on a platform which reciprocates on the main frame so as to render the pick machine adjustable longitudinally. The pick itself is mounted for vertical movement by 10 being pivoted to a carrier which supports the motor for swinging the pick in a vertical plane. The carrier itself is pivoted to the supplemental frame which supports a motor for swinging the carrier laterally together with the pick. This arrangement secures universal movement of the pick within the area over which it is intended to operate. The pick, therefore, commands the entire area of the mine heading. It should 20 be observed that inasmuch as the common source of supply L may be compressed air the motors for swinging the pick vertically and laterally may be operated by compressed air, in which event the pick or puncher will 25 be operated by yielding means to swing the same laterally and vertically. It is evident that if the pick strikes a glancing blow on the face of the coal or other material the air in the motor cylinder M² will permit the 30 piston N² to yield. In the same manner the air in the cylinder F³, as shown in Fig. 3, will permit the piston G³ to yield against the air within said cylinder.

From the foregoing description it will be 35 seen that by suitably manipulating valve A³, the operating medium will be delivered from chamber M', through pipe S², and passage of casing T², and valve A³, into either one or the other of pipes B³, C³, according to 40 the position of valve A³, the other of said pipes B³, C³, being at the same time opened to exhaust through pipes D³, E³ and Q', to reservoir G'.

If desired and as shown, I may employ 45 a similar arrangement for imparting the horizontal movements to the tool frame D on its vertical pivot stud E, as above explained, and which frame carries the cylinder M². The particular form of power 50 actuated device or motor for accomplishing this result is unimportant. In Fig. 3 I have shown a construction for accomplishing the desired result, comprising, a cylinder F³, in which operates a piston G³, to the rod 55 or stem H³ of which is connected a cross-head J³, one end of a link K³ being pivotally connected to the cross-head J³, the other end of said link being pivotally connected to a crank arm L³, connected to rock with 60 pivot stud E, said pivot stud being suitably splined or otherwise connected to the tool frame D to rock therewith, the parts shown and as above referred to for effecting the horizontal rocking movement of the tool

frame D being substantially identical in 65 every particular with the similar parts above referred to for effecting the vertical rocking or swinging movements. The operating medium, whether fluid such as compressed air or a liquid such as water, may 70 be supplied to and exhausted from cylinder F³ or otherwise controlled in any suitable or convenient manner, as, for instance, by means of a valve M³, arranged to control the supply and exhaust ports similar in all respects to the arrangement and operation of valve A³, above described. By employing water as the operating medium I secure the advantages of a lock for holding piston G³ in any desired position as above explained 80 with reference to piston N² and cylinder A'.

It is desirable, as above stated, to provide means for advancing the main frame A through the room or entry as the mining operation proceeds. It is also desirable to 85 provide means for efficiently locking or anchoring the main frame in its adjusted positions. These results may be accomplished in many specifically different ways. I have shown simple and efficient means for 90 accomplishing the result, wherein I employ anchor devices in the form of rods N³, and which at their outer or free ends are arranged to engage the walls of the room or entry through which the machine is to be 95 progressed. It is obvious that as many of these anchor rods may be employed as may be desired. I have shown three of such devices, one engaging the roof of the entry or room and one engaging each of the side 100 walls thereof, but I do not desire to be limited or restricted in this respect. These rods form piston rods for pistons O³, (see Fig. 1,) said pistons operating in cylinders P³, hinged or pivotally mounted, as at Q³, 105 upon the main frame A of the machine, and extending rearwardly and preferably in an outwardly inclined position, as clearly shown in the drawings. If desired, the cylinders P³ may be yieldingly pressed or 110 swung outwardly so that the outer free ends of rods N³ will normally engage or bear against the surface of the wall or sides of the room or entry. To this end I provide a spring R³, suitably connected at one end to a fixed part of the framework of the machine and at the other end to a tail-piece or extension S³, of cylinders P³; said tail-pieces projecting beyond the points of pivotal connection Q³ of the cylinders upon 115 the main frame. An operating medium may be admitted to the respective ends of each cylinder P³ in any convenient manner, so as to cause a relative longitudinal movement of pistons O³ and cylinders P³. In order 120 to effect the advancing movement of the main frame the outer ends of the rods N³ anchor or bear against the walls or ceiling 125

of the room or entry, and by admitting operating medium to the cylinders P^3 on opposite sides of the pistons O^3 , it will be seen that the main frame carrying the cylinders P^3 will be advanced or pushed forwardly, and by admitting operating medium to the other or outer ends of the cylinders the pistons O^3 will be moved into the cylinders, thereby drawing the arms N^2 into 10 the cylinders to enable the outer of the free ends thereof to gain a new engaging or anchoring place. In this manner the main frame may be advanced along the entry or room as it is made by the operation of 15 the mining tool H . As above indicated, however, the anchoring and advancing devices may be power actuated by any other suitable form of motor. That shown, however, I deem simple and efficient. Where 20 a pressure medium is employed as the operating medium I prefer to employ water, as thereby the operating medium forms a lock when both the supply and exhaust thereof is cut off from the cylinders P^3 , so as to 25 lock or hold the anchoring devices and hence the main frame in a position advanced or whatever position to which it may be advanced. Where water is employed as the operating medium, such medium may be 30 supplied from chamber M' in any convenient manner, as, for instance, through a pipe A^4 , delivering from chamber M' into a passage or chamber of casting T^2 , and which is controlled by a valve B^4 . An exhaust 35 pipe connection C^4 delivers from said passage into exhaust pipe E^3 , and thence through exhaust passage Q' into reservoir G' . Also communicating with the passage which is controlled by valve B^4 , are a system 40 of pipes D^4 , leading to corresponding ends of all of the cylinders P^3 , and also a system of pipes E^4 leading to opposite ends of all of the cylinders P^3 . Therefore, by suitably manipulating valve B^4 all of the cylinders 45 P^3 may be simultaneously opened to the source of supply of the operating medium at the same relative ends thereof, while at the same time the opposite ends of all of said cylinders are opened to exhaust. As 50 the parts are shown in Fig. 1, the valve B^4 is in position to open the outer ends of all of the cylinders P^3 to exhaust and the inner ends thereof to the source of supply of the operating medium.

55 In practice I propose to mount the pump cylinder J' and its actuating pump cylinder R' , the compressor cylinder G^2 , and casing T^2 , and the parts associated therewith, upon the sliding frame C ; and consequently the pipe connections to the various operating cylinders, except cylinders A' and F^3 , should be flexible connections to permit of the relative movements of the parts actuated thereby. This is unnecessary, however, so far as cylinders A' and F^3 are concerned, because said cylinders are mounted upon or formed to move with the sliding frame C .

As the mining operation progresses, the coal or other material detached by the operation of the tool would fall to the floor of the entry or room and there form an obstruction to prevent the advancement of the frame of the machine. It is necessary, therefore, to provide means for efficiently 70 removing the detached or mined material. Many specifically different constructions may be employed for accomplishing this result. While, therefore, I have shown and will now describe one form which I have 75 found efficient, I desire it to be understood that my invention is not to be limited or restricted to the specific construction shown. In the form shown I employ a scoop or shovel F^4 , and provide the same with arms 80 G^4 , which arms are mounted upon to turn with a transverse shaft H^4 , suitably journaled in a slide frame J^4 which latter is adapted to move in the guides J^6 . Any suitable form of motor may be employed for advancing the scoop or shovel F^4 , or retract the same. In practice, said scoop or shovel is arranged to move along or just above the surface of the floor of the room or entry in which the machine is working and at a point 85 beneath said frame, as clearly shown in Figs. 1 and 4, but by advancing frame J^4 upon the main frame through the guides J^6 the scoop or shovel F^4 may be advanced so as to scoop up any detached or accumulated coal or 90 other material mined by the tool, and so as to be advanced clear of the machine frame. In the particular form shown I employ a motor cylinder K^4 , upon the slide frame J^4 , in which cylinder is arranged to operate a 95 piston L^4 , the rod M^4 of which is fixed to the main frame. In this respect the motor is substantially the same in construction and operation as the cylinder A' , the cylinder being movable and the piston fixed, and by 100 supplying operating medium on one side or the other of the piston L^4 the slide frame J^4 may be shifted or moved in one direction or the other, as the case may be. An operating medium may be supplied to the cylinder K^4 105 in any convenient manner, as for instance, through supply pipes N^4 , O^4 , from a passage controlled by a valve P^4 , with which passage communicates or to which delivers main supply pipe L . While in the position in 110 which the parts are shown in Fig. 1, both the supply and exhaust are cut off by valve P^4 from cylinder K^4 , but by shifting valve P^4 in one direction or the other, either of the pipes N^4 or O^4 may be brought into communication with the source of pressure maintained in pipe L , and the other of said pipes N^4 , O^4 , opened to exhaust through the exhaust passage R^4 . In practice, I prefer to 115 employ a cylinder K^4 on each side of the 120

125

130

machine, as indicated somewhat diagrammatically in Fig. 4. In such event, the cylinder K^4 on one side of the machine is arranged to communicate with the cylinder on 5 the opposite side of the machine through suitable pipe connections, as indicated at S^4 , shown in both full and dotted lines in Fig. 5, so as to simultaneously admit or exhaust the operating medium to or from said cylinders. When the shoe or shovel F^4 has been advanced underneath the pile of coal or other material mined the entire shovel is 10 raised or rocked about the axis of stud H^4 , so as to elevate or raise the shoe F^4 , carrying 15 the end thereof in front of and over the shield or guard A^4 , until it is brought into inclined position to discharge the load carried thereby on the belt or carrier M^5 . The vertical rocking movement imparted to the 20 shovel or shoe F^4 for this purpose may be effected by any suitably arranged power actuating mechanism, as, for instance, by means of a piston, indicated in dotted lines at T^4 , Fig. 1, arranged to operate in a cylinder A^5 , the piston rod B^5 being connected to a cross-head C^5 , to which is pivotally connected one end of a link D^5 , the other end of said link being pivotally connected to a crank arm E^5 , attached to shaft H^4 . In 25 practice, I prefer to employ two cylinders A^5 , one on each side of the machine, as shown in Fig. 5, each provided with a piston T^4 , a cross-head, and a link D^5 , so that the shaft H^4 may be rocked from both ends thereof. 30 Any other suitable form of motor may be employed for effecting the rocking movement of the shovel F^4 . Where a piston and cylinder construction is employed I deliver an operating medium to opposite ends of 35 said cylinder in any convenient manner, as, for instance, through pipes F^6 , G^6 , said pipes delivering to a passage arranged to be controlled by a valve H^6 , and with which passage communicates the main pressure 40 medium supply pipe L , as, for instance, through passage J^6 , said passage also exhausting through port or passage K^6 . In the arrangement of these parts as shown the pipe F^6 is open to exhaust, while the pipe G^6 45 is open to the source of pressure medium. By suitably manipulating valve H^6 , the supply or exhaust to and from the cylinder A^6 may be readily controlled. In practice, the cylinders A^6 are arranged immediately above 50 the cylinders K^4 , and are suitably connected together by pipes, indicated at L^6 , whereby both the pistons T^4 of both cylinders may be simultaneously operated by the manipulation of a single control valve H^6 . By employing two motors, one on each side of the machine and each connected through links D^5 to the cranks E^5 , the shaft H^4 is 55 efficiently rocked to rock or swing the shovel F^4 vertically. 60 By elevating the shovel F^4 , the load of material carried thereby is permitted to discharge rearwardly therefrom. When thus discharged or delivered from the shovel F^4 , the material is received upon a suitable carrier, by which such material is delivered toward the rear of the machine. In practice I propose to employ a carrier mechanism which will not only receive and transport the material delivered thereto rearwardly of the machine, but into suitable cars or receptacles arranged to receive the same. I have shown a convenient arrangement of carrier mechanism for accomplishing the desired object, but to which I do not desire to be limited or restricted, and wherein I employ 65 traveling belts or conveyors M^5 , N^5 . The carrier M^5 is mounted upon rollers O^5 , P^5 , suitably journaled in the main frame of the machine, the roller P^5 being located at the front end of the main frame, and the roller O^5 in the rear part of the main frame and in a somewhat higher plane than roller P^5 , so as to give the carrier a vertical inclination rearwardly. The carrier N^5 operates over a roller Q^5 , suitably journaled in the main 70 frame and extends rearwardly and upwardly therefrom to a convenient point of delivery into a car or other receptacle. The carriers M^5 , N^5 , may be driven in any convenient manner. I have shown a simple arrangement, wherein the shafts of rollers O^5 , Q^5 , have spur gears R^5 , S^5 , mounted thereon, with both of which engages an intermediate spur gear T^5 , mounted upon a shaft A^6 , extending transversely of the machine, and to 75 which rotary motion may be imparted in any suitable or convenient manner, as, for instance, by means of a motor B^6 . The particular form of motor employed for this purpose is unimportant. I have shown a compressed air motor in the form of a cylinder, the pitman rod C^6 of which is connected to a wrist pin D^6 , on a disk E^6 , mounted on shaft A^6 . The operating medium may be supplied to the cylinder B^6 to operate a piston therein 80 in any convenient manner, as, for instance, through a supply pipe F^6 , (see Fig. 1,) which communicates at one end with the fluid pressure supply pipe L , and at the other end delivers into a valve chest G^6 , in 85 which may be arranged a valve similar in all respects to the valve P or the valve T , by which the supply of operating medium to the respective ends of the cylinder and to exhaust may be controlled in the ordinary 90 manner. A hand-valve H^6 , in pipe connection F^6 , may serve to cut off or turn on the pressure medium between main supply pipe L and the pipe connection F^6 . 95 Through the rotation of shaft A^6 a travel 100 is imparted to the carrier belts M^5 , N^5 . The material deposited upon the carrier M^5 by shovel F^4 is delivered from said carrier upon carrier N^5 , by which such material may be elevated and dumped or delivered into a 105 110 115 120 125 130

suitable or conveniently arranged car or receptacle.

In operation, an attendant occupying a position upon sliding frame C, is enabled to readily control the several valves above referred to, and through which the various mechanisms described are operated. It will be observed that in operation the main frame is advanced along the room or entry as the same is formed through the mining operation, said main frame being forced forwardly by the anchor rods when the latter are suitably actuated, and is locked or anchored in advanced position to take the recoil or shock resulting from the delivery of the blow of the mining tool. It will also be observed that the tool is supported and mounted so as to be capable of swinging in both horizontal and vertical planes without interruption of the continuous reciprocatory movements thereof, the mechanisms employed for effecting the vertical and horizontal swinging movements of the tool being independent of each other and under the efficient control of the operator. It will also be observed that by supporting the mining tool upon a frame mounted to slide in the main frame, such tool may be advanced to its work upon the main frame, the latter remaining anchored and stationary until the tool has sufficiently completed its work within the area commanded thereby to permit the main frame to be again advanced. It will also be observed that although compressed air may be used by employing hydraulic means for advancing the sliding frame which carries the mining tool and also for operating the mechanism for imparting the swinging movements to the mining cutter, I am enabled to hydraulically lock the parts whenever desired, thereby forming, in effect, an anchor for resisting or taking up the shock due to the delivery of the blow of the mining tool, and hence rigidly holding the parts in the positions to which they have been actuated by the hydraulic mechanism. It will also be seen that by partially withdrawing the scoop or shovel F⁴ underneath the main frame said main frame is enabled to be advanced closely up to the point of application of the mining tool, and thereafter as the mining operation proceeds the shovel may be advanced from beneath the main frame and underneath the pile of accumulated material mined or detached by the mining tool, and then elevated or raised so as to transfer the mined material to the carriers, by which such material is delivered to a point in the rear of the machine, enabling the same to be readily and quickly removed from the room or entry and without interruption of the continuous operation of the machine.

In transporting the machine to and from the place where it is required for use, it may sometimes be desirable to detach the sup-

plemental delivery carrier N⁵ or to remove the same from danger of accident, or from position forming an obstruction to the ready access to the machine. To accomplish this result, I provide the main frame with trackways A⁸ (see Figs. 1, 2, 4 and 5), in which are received the ends of the shaft B⁸, over which supplemental carrier N⁵ operates. By this construction it will be readily seen that when the auxiliary delivery carrier N⁵ is not required, the shaft B⁸, on which gear S⁵ is mounted, is shifted or moved so as to detach said gear S⁵ from engagement with its drive gear T⁵, and said shaft is then shifted or moved with the ends thereof traveling along the guides A⁸, thereby enabling the auxiliary carrier N⁵ to be housed within the main frame of the machine.

It is believed that the construction, function and mode of operation of the various devices above described will be readily and fully understood from the foregoing description, when taken in connection with the accompanying drawings.

Obviously those skilled in the art may make various changes in the details and arrangement of parts without departing from the spirit and scope of my invention as defined by the claims hereto appended. I desire, therefore, not to be restricted to the precise construction disclosed nor to any particular operating medium for the various motors. While the term "mining tool" is intended to be construed broadly, I wish the term "pick machine" wherever used in the claims to be understood as of that type wherein the pick is operated percussively or by quick, repeated blows.

Having now set forth the object and nature of my invention, and a construction embodying the principles thereof, what I claim as new and useful and of my own invention, and desire to secure by Letters Patent, is:

1. In a mining machine, a main frame, a reciprocating mining tool mounted thereon for universal movement, and means for actuating said mining tool, in combination with fluid-pressure power-actuated mechanism for advancing and anchoring said main frame.
2. In a mining machine, a main frame, a mining tool carried thereby and means for operating said tool, in combination with independent anchor arms having pivotal connection with the main frame, separate means for yieldingly swinging said arms in a direction for the free ends thereof to engage the walls or roof of the room or entry in which the machine operates, and fluid pressure power mechanism for operating said arms to advance the machine along the room or entry.
3. In a mining machine, a main frame, an auxiliary frame slidably mounted upon the main frame, a reciprocating mining tool

130

- carried by said auxiliary frame, and mounted therein for universal movement with respect thereto, means for operating said mining tool, means for advancing said sliding frame upon said main frame, and means for advancing the main frame.
4. In a mining machine, a main frame, an auxiliary frame slidably mounted upon said main frame, a mining tool pivotally carried by said auxiliary frame, means for actuating said mining tool, means for moving the tool about its pivot and power-actuated mechanism for advancing said sliding frame upon said main frame.
5. In a mining machine, a main frame, a supplemental frame slidably mounted upon said main frame, a mining tool carried by said supplemental frame and mounted for universal movement thereon, means for operating said mining tool, a cylinder and piston, one of these parts connected to said sliding frame and the other to said main frame, and means for controlling the supply and exhaust of an operating medium to said cylinder to advance said sliding frame upon said main frame.
6. In a mining machine, a main frame, a supplemental frame slidably mounted upon said main frame, a mining tool carried by said supplemental frame and mounted for universal movement thereon, means for operating said mining tool, and a fluid pressure motor for advancing said sliding frame upon said main frame.
7. In a mining machine, a main frame, a supplemental frame slidably mounted thereon, a mining tool carried by said supplemental frame and mounted for universal movement thereon, means for operating said mining tool, a piston and cylinder, one of these parts connected to said sliding frame and the other to said main frame, means for supplying fluid to said cylinder, and a valve controlling the supply and exhaust of the fluid to said cylinder, whereby said sliding frame is advanced upon said main frame and is anchored in advanced position.
8. In a mining machine, a frame, a mining tool, a carrier bodily adjustable upon the frame and upon which said tool is pivotally mounted, power-actuated mechanism for rocking or swinging said tool about its pivotal support upon said carrier, and means for operating said tool.
9. In a mining machine, a frame, a carrier bodily adjustable upon the frame, a pivot-stud connecting said carrier and frame, a motor connected to said stud for rocking the same, a mining tool supported by said carrier, and means for operating said tool.
10. In a mining machine, a frame, a carrier movable with respect to the frame, a stud pivotally connecting said carrier and frame, a motor connected to said stud for rocking the same, a tool supported upon said carrier, means for operating said tool, and means for independently controlling the supply and exhaust of fluid to said fluid pressure motor whereby said carrier and
- rocking the same, a tool supported upon said carrier, means for operating said tool, and means for controlling said motor.
11. In a mining machine, a frame, a carrier pivotally mounted upon and movable with respect to said frame, a motor connected to said carrier for rocking the same about its pivot, a mining tool mounted on said carrier, and means for operating said tool.
12. In a mining machine, a frame, a carrier pivotally mounted upon said frame, a motor for rocking said carrier about its pivotal connection with said frame, a tool support pivotally mounted upon said carrier, means for rocking said tool support about its pivotal connection with said carrier, and means for operating the tool.
13. In a mining machine, a frame, a carrier pivotally mounted thereon to swing, a tool support pivotally mounted upon said carrier, a tool carried by said support, means for operating said tool, and fluid controlled means for independently rocking said tool support and carrier.
14. In a mining machine, a frame, a carrier pivotally mounted upon said frame, a tool support pivotally mounted upon said carrier, a tool carried by said support, means for operating said tool, a motor connected to rock or swing said tool support, an independent motor connected to rock said carrier, and means for independently controlling said motors.
15. In a mining machine, a frame, a carrier pivotally mounted thereon, a motor connected to rock or swing said carrier about its pivot, a tool support pivotally mounted upon said carrier, a motor connected to rock or swing said support about its pivot on said carrier, a mining tool carried by said support, means for operating said tool, and means for independently controlling the operation of said tool and of said motors.
16. In a mining machine, a frame, a carrier pivotally mounted thereon, a fluid pressure motor connected to rock or swing said carrier about its pivot on said frame, a tool carried by said carrier, means for operating said tool, and means for controlling the supply and exhaust of pressure medium to said motor, whereby said carrier may be rocked or swung and anchored in position.
17. In a mining machine, a frame, a carrier pivotally mounted thereon, a fluid pressure motor connected to said carrier to rock the same about its pivot, a tool support pivotally mounted upon said carrier, a fluid pressure motor connected to said tool support for rocking the same about its pivot on said carrier, a mining tool carried by said support, means for operating said tool, and means for independently controlling the supply and exhaust of fluid to said fluid pressure motor whereby said carrier and

support may be independently rocked or swung and locked in position.

18. In a mining machine, a frame, power mechanism for reciprocating the same, a reciprocable mining tool pivotally supported upon said frame, means for reciprocating said tool, and means for rocking said tool about its pivotal support upon said frame.

19. In a mining machine, a frame, fluid-
10 pressure power-actuated mechanism for reciprocating the same, a reciprocable mining tool pivotally supported upon said frame, and independent mechanism for reciprocating said tool and for rocking the same about 15 its pivotal support upon said frame.

20. In a mining machine, a frame, power-
actuated mechanism for reciprocating the same, means for controlling said power mechanism, a reciprocable mining tool piv-
20 tally supported upon said frame, means for reciprocating said tool, and power mechanism for rocking said tool about its point of pivotal support upon said frame.

21. In a mining machine, a mining tool
25 mounted for universal movement, power mechanism for actuating said tool, in combination with a support for said tool about its universal mounting, a carrier upon which said support is pivotally mounted, a frame
30 upon which said carrier is pivotally mounted, and independent fluid controlled power mechanisms for rocking said support and carrier about their pivots.

22. In a mining machine, a reciprocable
35 mining tool, and means for operating the same, in combination with a support for said tool, a carrier upon which said support is pivotally mounted to rock or swing vertically, a frame upon which said carrier is
40 pivotally mounted to rock or swing horizontally, independent power mechanisms for rocking said carrier and support, and controlling devices for said power mechanisms, said controlling devices being carried by
45 said frame.

23. In a mining machine, a reciprocable mining tool, means for operating the same, a support for said tool, a carrier upon which said support is pivotally mounted, a frame
50 upon which said carrier is pivotally mounted, power mechanisms for rocking said carrier and support about their pivots, power mechanism for moving said frame, and controlling devices for said several
55 power mechanisms, said controlling devices being carried by said frame.

24. In a mining machine, a reciprocable mining tool, means for reciprocating said tool, a support for said tool, a carrier upon
60 which said support is pivotally mounted, a supplemental frame upon which said carrier is pivotally mounted, a main frame upon which said supplemental frame is
65 movably mounted, fluid pressure mecha-

nism for moving said supplemental frame
and for rocking said carrier and support
about their pivots, said fluid pressure mech-
anism being carried by said supplemental
frame.

25. In a mining machine, a reciprocable
mining tool, means for reciprocating said
tool, a supplemental frame, said tool piv-
otally supported upon said supplemental
frame, a main frame upon which said sup-
plemental frame is mounted to move, and
70 independent motors carried by said sup-
plemental frame for moving the latter and
for swinging said tool, and controlling de-
vices for said motors, said controlling de-
vices also carried by said supplemental
frame.

26. In a mining machine, a reciprocable
mining tool, means for operating the same,
a frame upon which said tool is mounted
for swinging movement in a vertical and
85 horizontal direction, motors carried by said
frame for controlling the swinging move-
ments of said tool, and means for independ-
ently controlling said motors.

27. In a mining machine, the combina-
tion of a single, universally movable recip-
rocatory pick, a conveying means arranged
underneath and below the plane of action of
the pick for receiving and conducting away
95 the particles dislodged by the pick, and
means whereby the pick may be adjusted to-
ward and from the work independently of
its reciprocatory and universal motion and
independently of said conveying means.

28. In a mining machine, a reciprocable
mining tool, means for operating said tool,
means for individually supporting the tool
for swinging movement in vertical and hori-
zontal directions, means for imparting such
movements to the tool as to adjust the same
100 to any desired radial position, a scoop and
means for operating same and means operat-
ing below the plane of operation of said tool
for directly receiving the dislodged material
105 from said scoop and immediately carrying
it away.

29. In a mining machine, a pick, means
for advancing the pick in the mine to the
work and at various angles to the work, a
carrier arranged directly below the plane of
action of the pick for receiving the mate-
rial after it is dislodged by said pick and
115 for carrying away the dislodged material,
and means for transferring the material to
said carrier.

30. In a mining machine, a pick, fluid
power actuating mechanisms engaging the
walls of the mine for advancing the pick in
the mine and work at various angles to the
work, a carrier operating close to the floor
120 of the entry directly below the plane of ac-
tion of the cutter for removing the dis-
lodged material, and means for taking up

- the material and discharging it onto said conveyer.
31. In a mining machine, a frame, a tool carrier mounted in said frame for movement about axes intersecting each other, fluid pressure actuated mechanism for moving the carrier about its axes, a tool reciprocably mounted upon the carrier, and means for reciprocating the tool.
32. In a mining machine, a frame, a tool carrier mounted upon said frame, for movement about axes intersecting each other, fluid pressure power actuated mechanism for moving the carrier about its axes, a tool reciprocably mounted upon the carrier, means for reciprocating the tool, a conveyer operating in a plane below the tool and means for receiving and delivering the dislodged material to the conveyer.
33. In a mining machine, a frame, a tool carrier mounted upon said frame, for movement about axes intersecting each other, fluid pressure power actuated mechanism for moving the carrier about its axes, a tool reciprocably mounted upon the carrier, means for reciprocating the tool, a conveyer operating in a plane below the tool, a scoop for receiving and delivering the dislodged material to the conveyer, and means for actuating the scoop.
34. A mining machine including a portable platform, a puncher mounted thereon, and yielding means for swinging the puncher laterally.
35. A mining machine including a portable platform, a puncher mounted thereon, yielding means for swinging the puncher laterally and yielding means for swinging the puncher vertically.
36. A mining machine including a portable platform, a puncher mounted thereon, means for adjusting the puncher longitudinally, and yielding means for swinging the puncher laterally.
37. A mining machine including a portable platform, a puncher mounted thereon, means for adjusting the puncher longitudinally and yielding means for swinging the puncher vertically.
38. A mining machine including a portable platform, a puncher mounted thereon, means for adjusting the puncher longitudinally, yielding means for swinging the puncher laterally and yielding means for swinging the puncher vertically.
39. A mining machine including a portable platform, a support mounted thereon, yielding means for swinging the support horizontally and a puncher mounted on said support.
40. A mining machine including a portable platform, a support mounted thereon, yielding means for swinging the support horizontally, a puncher mounted on said sup-
- port and means for swinging the puncher vertically.
41. A mining machine including a portable platform, a support mounted thereon, yielding means for swinging the support horizontally, a puncher mounted on said support and yielding means for swinging the puncher vertically.
42. In a mining and loading machine, the combination with a frame, of a pick machine mounted on said frame, a rearwardly extending conveyer on the frame beneath the pick machine, and means for taking the broken down material and moving it onto said conveyer.
43. In a mining and loading machine, the combination with a supporting frame, of a pick machine mounted thereon, a conveyer carried by said frame, a scoop in position to receive the material dislodged by said pick machine and move it onto said conveyer, and means for feeding the frame forwardly.
44. In a mining and loading machine, the combination with a frame, of a pick machine mounted on said frame for universal movement, and means arranged under and related to said pick machine for scooping up and carrying away the dislodged material.
45. In a mining and loading machine, the combination with a main frame, a supplemental frame mounted on said main frame for reciprocatory movement, a pick machine mounted on said supplemental frame for universal movement, and a loading apparatus for removing the dislodged material and carrying it away.
46. In a mining and loading machine, the combination with a pick machine comprising a reciprocatory pick and means for operating the same percussively, of apparatus for swinging said pick machine laterally and vertically to command the entire area of the mine heading, a conveyer for loading the dislodged material, and means for moving the material onto said conveyer.
47. In a mining and loading machine, the combination with a universally mounted pick, of means for operating said pick percussively, a conveyer for carrying the dislodged material away from the mine wall, and means for taking fallen dislodged material and moving it onto said conveyer.
48. In a mining and loading machine, the combination with a frame, of a pick machine mounted on said frame, a conveyer mounted on said frame, means cooperatively related to said conveyer for taking the material broken down by said pick machine and moving it onto said conveyer, and means for operating said pick machine, conveyer and said means for moving the material onto said conveyer.
49. In a mining and loading machine, the

combination with a frame, of a conveyer mounted on said frame, a mining tool mounted on said frame, means for operating said mining tool, and means operable independently of said mining tool for taking the material broken down by said tool and moving it onto said conveyer.

In witness whereof, I have hereunto set my hand this 25th day of May, 1904, in the presence of the subscribing witnesses.

EDMUND C. MORGAN.
